The 10 best cloth face masks we tested (5. Vistaprint Face Mask), available in usatoday.com, announced Jun. 29, 2020 [online], [site visited Apr. 15, 2022], Internet URL: <https://www.usatoday.com/story/tech/reviewedcom/2020/06/29/10-best-cloth-face-masks-we-tested-athleta-tom-bihn-and-more/3278947001/> (Year: 2020).*

Primary Examiner — Jennifer L Rempfer*Assistant Examiner* — Elizabeth Anne Glassberg(74) Attorney, Agent, or Firm — Whitewood Law PLLC; Shengmao Mu(57) CLAIM

What is claimed is an ornamental design for a face mask, as shown.

DESCRIPTION

FIG. 1 is a perspective view of a face mask showing our new design;

FIG. 2 is a frontal elevational view thereof;

FIG. 3 is a rear elevational view thereof;

FIG. 4 is a top view thereof;

FIG. 5 is a bottom view thereof; and,

FIG. 6 is a side elevational view thereof.

The broken lines in the figures illustrate portion of the face mask that form no part of the claimed design.
